W. WESTBURY,
GLASS FURNACE.
APPLICATION FILED JUNE 26, 1917.

1,294,581.

Patented Feb. 18, 1919.

Attorney

UNITED STATES PATENT OFFICE.

WILLIAM WESTBURY, OF OKMULGEE, OKLAHOMA, ASSIGNOR TO L. SHERMAN SKELTON,
OF OKMULGEE, OKLAHOMA.

GLASS-FURNACE.

1,294,581.

Specification of Letters Patent. Patented Feb. 18, 1919.

Application filed June 26, 1917. Serial No. 176,955.

To all whom it may concern:

Be it known that I, WILLIAM WESTBURY, a citizen of the United States, residing at Okmulgee, in the county of Okmulgee and 5 State of Oklahoma, have invented new and useful Improvements in Glass-Furnaces, of which the following is a specification.

This invention relates to improvements in glass furnaces, and particularly to tank furnaces employed in connection with glass drawing apparatus of the kind having one or more drawing stations in the form of forehearths or doghouses, such as shown, for example, in my prior Patent No. 1187025, 10 dated June 13, 1916, the primary object of the invention being to provide an improved mode of constructing the top and breast walls of the forehearth or doghouse whereby increased strength and durability are obtained.

A further object of the invention is to provide a construction which facilitates the work of constructing and repairing such walls, which secures increased protection 15 against disintegration by the action of heat, and which reduces sagging, warping and other distortions to a material degree.

A still further object of the invention is to provide simple and effective means for 20 supporting and cooling the parts subjected to intense heat.

The invention consists in the features of construction, combination and arrangement of parts more fully hereinafter described 25 and claimed, reference being had to the accompanying drawing, wherein:

Figure 1 is an enlarged front-to-rear section taken centrally through the doghouse, or forehearth at one portion of the furnace, 30 the plane of section being indicated by the line 1-1 of Fig. 4;

Fig. 2 is a perspective view of one of the blocks composing the top wall;

Fig. 3 is a horizontal section through two 45 of the blocks composing the breast wall; and

Fig. 4 is a plan view, on a reduced scale, of the forehearth or doghouse.

Referring to the drawing, 1 designates the 50 top or crown wall of the furnace body, 2 the forehearth or doghouse, 3 the front wall of the forehearth or doghouse bounding the reservoir chamber 5 thereof, 6 the top wall of the doghouse, and 7 the curved lintel or 55 breast wall connecting the wall 6 with the top wall 1 of the furnace body. The top

wall 6 of the doghouse is arranged to extend within a semi-circular recess 8 formed in the front wall of the furnace by offsetting a correspondingly shaped portion of said front wall inwardly in the form of the curved lintel or breast wall 7, thus allowing the drawing opening 9 in the top wall 6 of the doghouse to be so arranged that one-half of said opening is arranged beyond the line 60 of the front furnace wall, while the remaining half of the opening is arranged wholly within the line of said front furnace wall, whereby the advantages due to this construction as set forth in my aforesaid patent 65 are gained.

It is found in practice that the walls 6 and 7 are subject to disintegration, sagging, warping and other distortions, owing to the intense heat, as well as to the variations of 70 temperature to which they are subjected. When either one or both of these walls is disintegrated, distorted or cracked to a certain degree, it is necessary to shut down the furnace in order to make repairs, a tedious 75 and expensive operation. The object of the present invention is to provide a construction whereby these walls will be protected to a greater extent against the action of heat and also against variations of temperature, 80 whereby the walls may be quickly and conveniently set up and repaired when necessary, and whereby the walls are strengthened and more rigidly and durably sustained and supported. To this end the 85 curved breast wall 7 is made of a series of vertically disposed blocks or tiles 10, having their meeting faces provided with tongue-and-grooved connections 11 and 12, thereby adapting said blocks to be fitted in position 90 and removed in a ready and convenient manner. By this construction it will be evident that the wall 7 may be readily and conveniently constructed and as readily and conveniently repaired, and that one or more 95 damaged blocks may be removed and replaced whenever required without requiring the replacement of the others.

The wall 6 is also composed of blocks 13, and these blocks 13 are provided with curved 100 or segmental inner edges 14 which coöperate, when the blocks are assembled, to form the drawing opening. The blocks 13 have their upper faces cut away on their inner sides, to form concaved portions 15, and have their 105 outer portions plane surfaced, as indicated at 16, to abut against the lower ends of the

blocks 10 and form base supports for said blocks 10. Alined openings 17 are formed in the blocks 13, and these openings form a channel extending in horseshoe form around the drawing opening and opening at the front of the doghouse on opposite sides of the drawing opening. These openings 17 receive a supporting member consisting of a pipe or conductor 18 having threaded openings 19 in its upper side, with which are connected the lower threaded ends of supporting rods 20 extending upwardly through receiving recesses 21 in the blocks 10 and openings 22 in the blocks 13 and connected at their upper ends with the usual beams 23 of the reinforcing or truss frame for the walls of the furnace.

It will thus be understood that the blocks forming the wall 6 may also be readily applied and removed, and that consequently repairs of this wall may be conveniently made when the occasion requires. It will be observed that the concaved portions 15 of the blocks 10 form an annular channel around or dished portion in the wall 6 above and beyond the line of the drawing opening 9, whereby the upper portion of the wall 6 about the drawing opening will be protected from the heat radiating from the glass cylinder being drawn, the channeled or dished portion also allowing free radiation of the heat. By disposing the supporting rods 20 within the recesses 21, these rods are also protected, and the recesses provide air channels whereby the walls are more reliably cooled and protected from the heat, as well as excessive variations of temperature. The conductors 18 not only reinforce the blocks 13 but provide a means for durably connecting said blocks with the supporting rods 20, and also serve as conductors whereby a cooling fluid of a desired kind may be circulated through the blocks to further protect the walls from the heat. The pipe 18 is shown as projecting at one end 24 for connection with a suitable source of supply of a cooling fluid or liquid, such as water, steam or the like, and projecting at its opposite end 25 for connection with a drain pipe or the like when water is used as a cooling medium. By thus circulating a cooling fluid through the wall 6 about the drawing opening the said wall 6, as well as the wall 7, is better protected against disintegration, cracking, warping and other distortions and the period of usefulness of such portions of the furnace considerably prolonged.

I claim as my invention:

1. In a forehearth construction for glass furnaces, the combination of a furnace top wall, a horizontal forehearth top wall including block segments forming a drawing opening, a U-shaped supporting member extending partially around the drawing opening

and embedded in the blocks and upon which said blocks are slidably mounted, an overhead support, and supporting elements secured to said overhead support and to said supporting member for supporting said block segments in position.

2. In a forehearth construction for glass furnaces, the combination of a furnace top wall, a forehearth top wall composed of block sections arranged to form a drawing opening, a curved breast wall extending between the furnace top wall and forehearth top wall and resting at its lower edge upon the latter, a U-shaped supporting member extending partially around the drawing opening and embedded in the block segments of the forehearth top wall and upon which said block segments are slidably mounted, an overhead support, and a series of supporting rods extending around the front of the breast wall and connecting said supporting member with said overhead support.

3. In a forehearth construction for glass furnaces, the combination of a furnace top wall, a horizontal forehearth top wall including block segments forming a draw opening, a fluid conductor upon which said block segments are slidably mounted, an overhead support, and supporting elements secured to said overhead support and to said conductor for supporting said block segments in position.

4. In a forehearth construction for glass furnaces, the combination of a furnace top wall, a forehearth top wall composed of block segments arranged to form a drawing opening, a supporting element extending partially around the drawing opening and embedded in and connecting said block segments, a breast wall partially surrounding the forehearth top wall and composed of block sections resting on said block segments and extending between the same and the furnace top wall, an overhead structure, and rods extending downwardly from said structure at the front of the breast wall and connected with the embedded supporting element in the block sections of the forehearth top wall.

5. In a forehearth construction for glass furnaces, the combination of a furnace top wall, a forehearth top wall composed of a series of block sections arranged to form a drawing opening, a curved breast wall partially surrounding the drawing opening and composed of block sections resting upon the forehearth top wall, said block sections of breast wall being provided with grooves or recesses in the front face thereof, supporting elements embedded in the block segments of the forehearth top wall, an overhead supporting structure, and rods extending downwardly from said overhead supporting structure through the said grooves or recesses in

- the breast wall and connected with said supporting elements embedded in the forehearth top wall.
6. In a forehearth construction for glass furnaces, the combination of a furnace top wall, a forehearth top wall forming a drawing opening, a breast wall extending between said top walls, a conductor extending around the drawing opening and embedded in the 5 forehearth top wall and having terminal portions projecting at the front of the dog-house, and overhead supporting elements connected with said conductor and coöperating therewith to support the said forehearth top wall and breast wall.
7. In a forehearth construction for glass furnaces, a forehearth top wall comprising a U-shaped supporting member, a series of assembled block segments having communicating openings for the passage of said supporting member, said block segments being slidably mounted on said supporting member and having arcuate inner edges, said arcuate edges of the assembled block segments 10 collectively forming a drawing opening, and the top surfaces of said block sections being cut away on concaved lines above the plane of said arcuate edges, forming a channel in the wall above and beyond the line of the drawing opening, and overhead supports for the block segments entering said block segments and connected with said U-shaped supporting member.
8. A forehearth having a top wall provided with a drawing opening, and a conductor for the circulation of a cooling 15
- medium embedded in said top wall and extending around the sides and rear of the drawing opening.
9. A forehearth for glass drawing furnaces having a top wall provided with a drawing opening, and a conductor extending around the rear and sides of the drawing opening and embedded in said top wall, said conductor having terminal portions projecting 20 outwardly at the front of the forehearth.
10. A forehearth for drawing furnaces having a top wall provided with a drawing opening, the upper surface of said wall being concaved to form an annular dished portion disposed at an angle to and surrounding the drawing opening and of greater diameter than said opening.
11. In a forehearth construction for glass furnaces, the combination of a furnace top 25 wall, a horizontal forehearth top wall composed of a series of block segments, connecting means for slidably holding said sections assembled, a vertical breast wall composed of slidably connected block sections resting at their lower ends upon the upper surface of the forehearth top wall and resting at their upper ends against the front edge of the furnace top wall, an overhead supporting structure, and rods or the like depending 30 from said overhead supporting structure on a line between the drawing opening and outer surface of the breast wall and connected at their lower ends with the segments of the forehearth top wall.
- In testimony whereof I affix my signature.
- WILLIAM WESTBURY.
